(57) **CLAIM**

The ornamental design for a four-wheeled push vehicle, as shown and described.

DESCRIPTION

FIG. 1 is a perspective view of a four-wheeled push vehicle with the front wheels turning to the right, showing my new design;

FIG. 2 is a side elevational view of a four-wheeled push vehicle with the rear wheels on the left and the front wheels on the right, showing my new design;

FIG. 3 is a front elevational perspective view thereof, showing my new design;

FIG. 4 is a rear elevational perspective view thereof, showing my new design;

FIG. 5 is a top perspective view of a four-wheeled push vehicle thereof, showing my new design; and,

FIG. 6 is a bottom perspective view of a four-wheeled push vehicle thereof, showing my new design.
